UNITED STATES PATENT OFFICE.

EDWARD HENRY FRIEND AND ALBERT GILEAD BENTLEY, OF HOLBORN, LONDON, ENGLAND, ASSIGNEES TO THE FRIEND BENTLEY ELEMENTS COMPANY LIMITED, OF MELBOURNE, AUSTRALIA, A CORPORATION OF VICTORIA, AUSTRALIA.

INTERNAL-COMBUSTION ENGINE.

Application filed September 17, 1925, Serial No. 56,874, and in Great Britain October 18, 1924.

This invention relates to Diesel and other liquid fuel injection internal combustion engines of the kind in which a fixed abutment of piston type is employed, upon which a 5 reciprocating piston of sleeve type slides.

According to this invention the piston of sleeve type moves within a cylinder, the upper or outer end of which is partly closed by a fixed abutment of cylindrical form and 10 of a diameter smaller than the internal diameter of the cylinder, leaving room for the sleeve portion of the piston to slide upon the abutment and within the fixed cylinder, the piston thus forms two combustion spaces 15 of different capacities, one inside the sleeved portion between the piston head and the end of the fixed abutment and the other between the piston head and the lower cylinder cover. Liquid fuel is injected into each combustion 20 space by injection valves fitted respectively in the fixed abutment, so as to inject the liquid fuel into the space within the piston sleeve, and in the lower part of the cylinder, so as to inject the liquid fuel into the cylinder 25 between the piston head and the cylinder cover. A sliding fluid tight joint between the fixed abutment and the inner face of the piston sleeve is made by piston rings carried by the lower portion of the abutment 30 and the piston head is, of course, also provided with the usual piston rings to form a fluid tight sliding joint with the fixed cylinder. The bottom cylinder cover is preferably carried by the outer wall or jacket 35 of the cylinder and projects into the lower end of the inner cylinder wall or liner, a gas tight joint being made by rings of piston ring type fitted to the inwardly projecting portion of the cylinder cover.

40 The piston, fixed abutment and cylinder end or cover are liquid cooled (usually water or oil but for convenience referred to herein-after as water cooled) and to provide for efficient cooling of the piston and sleeve wall 45 the piston may be fluted, thereby providing a large number of water channels leading from the upper end to the hollow piston head and communicating with the internal water space of the piston through passages 50 at the lower end of the fluting. On the outer side of the piston sleeve is fitted a water jacket sleeve which binds tightly on the fluted wall and has a sliding fit with the cylinder.

In order that the said invention may be 55 clearly understood and readily carried into effect, the same will now be described more fully with reference to the accompanying drawings, in which:—

Figures 1 and 2 are vertical sections of 60 an engine embodying this invention, the sections being taken at right angles to one another and showing the piston at opposite ends of its stroke; and

Figures 3 and 4 are horizontal sections 65 taken respectively on the lines $x-x$ and $y-y$ of Figure 2.

Figure 5 is a horizontal section taken on the line $z-z$ of Figure 1 through the upper 70 end of the sleeved piston.

A is the cylinder liner. B is the piston with piston sleeve C. D is the fixed abutment. E is the bottom cylinder cover. F is the trunnion ring carrying external trunnions f to which the small ends g of the connecting rods G are connected. H is the lower part of the engine frame comprising supporting legs mounted on the base H^1 and carrying at the upper end the exhaust and air inlet box or casing J cast in one with the outer cylinder wall a . K is the upper end of the frame or casing mounted on top of the box J and comprising fixed guides k at one side of the engine, with which cooperate slides f^1 on the trunnion ring F. L 85 is the crank shaft to which the large ends g^1 of the connecting rods G are connected at opposite sides of the engine. The drawings show the invention as applied to a single cylinder but it is of course equally 90 applicable to a single cylinder or a multi-cylinder engine.

The fixed abutment D, which is cooled, is supported from the detachable fixed cross member M by the tubular rods m which are 95 made hollow for the admission and outlet of cooling liquid into and from the water space d of the abutment, which may carry a central fuel injection valve d^1 and other necessary valves. The cross member M is mounted on 100 top of the upper frame or casing K.

It will be seen that the sleeve C of the piston B slides between the cylinder A and the abutment D, so that one combustion space N is formed within the sleeve B between the piston and the lower end of the abutment D while the second combustion space N^1 is 105 formed between the under surface of the

piston B and the bottom cylinder cover E. It will be observed that whereas in the normal design of double acting engine the lower combustion space is obstructed by the 5 piston rod and gland, in this design both spaces are symmetrical and free from obstruction so that the flame propagation is free and similar in both spaces. The abutment carries piston rings d^2 to form a sliding joint for the piston sleeve and the piston is provided with the piston rings b to form a fluid tight sliding joint with the fixed cylinder A. The outer wall or jacket a of the cylinder carries the bottom cylinder cover E, 10 which is secured in place by the ring e and the studs e^1 , a pressure tight joint being provided between the cover and the lower end of the cylinder liner A by the rings e^2 . This attachment allows the cylinder cover to be 15 readily removed from the bottom of the cylinder by removing the studs e^1 and ring e , when the cover is free to drop; or the cover can be drawn upwards through the cylinder. 20

It will be seen that the two working spaces 25 N N^1 are of different diameters, the lower space N^1 having the inner diameter of the fixed cylinder liner A, while the upper working space N has the inner diameter of the piston sleeve C, so that the two spaces differ by the thickness of the piston sleeve, thus 30 providing for a more powerful stroke from the lower combustion space to compensate for the extra work called for on the upward stroke in raising the moving parts.

35 In double acting engines of the normal type the lower combustion space is of the same diameter as the upper combustion space, and the area of lower combustion space is reduced by the area of the usual piston rod. These features, in conjunction with the obliquity of the connecting rods result in the power transmitted from the lower combustion space to the crank shaft being substantially less than that from the upper combustion space. In this design, however, as 40 the lower combustion space is of larger diameter than the upper, and as the area of the lower combustion space is not reduced by the introduction of a piston rod, and further as 45 the connecting rod obliquity is reduced since the rods are much longer than in normal types of engine, it is possible, by suitably proportioning the parts, to provide for substantially equal power to be transmitted to 50 the crank shaft from both the upper and lower combustion spaces, thus ensuring a uniform torque on the crank shaft.

55 The cooling water space a^1 for the cylinder is formed partly inside the liner A and 60 partly between the liner and the outer wall a . The water cooling of the piston is provided for by fluting or recessing the piston sleeve, adjacent its lower end as at c , forming a number of longitudinally arranged water 65 channels c and narrow passages c^x and cov-

ering the recess at the lower end of the sleeve by a water jacket sleeve c^1 which binds tightly on the piston and has a sliding fit within the cylinder. The upper ends of the channels c^x communicate by means of radially arranged holes c^5 with a pair of grooves or recesses c^3 formed in the periphery of the upper end of the sleeved piston, and the lower end of the recess c is in communication with the inside of the piston head by way of the passages c^7 . The cooling water is supplied and withdrawn through the supply and outlet pipes f^2 which are connected to the trunnion ring F, so that one of the pipes f^2 is in communication with one of the 70 grooves c^6 and the other pipe f^2 is in communication with the other groove. 75

The upper end of the piston sleeve C is fitted into the lower side of the trunnion ring and secured thereto by the bolts or 80 studs f^3 .

85 The piston sleeve C is provided with the inlet ports c^2 and exhaust ports c^3 at opposite sides, the inlet ports being shorter than the exhaust so that the inlet is open for a shorter period than the exhaust, these ports serving, of course, for the combustion space N only. The ports register, respectively, with the inlet and exhaust ports a^2 , a^3 of the cylinder A when the piston is at the outer 90 end of its downward stroke, these cylinder ports opening, respectively, into the inlet and exhaust channels j , j^1 of the casing or box J surrounding the middle of the cylinder. The cylinder is provided with the corresponding inlet and exhaust ports a^5 , a^6 situated below the ports a^2 , a^3 and serving for the lower combustion space N^1 , the ports being opened when the piston approaches the end of its upper stroke. The arrangement of ports illustrated is one suitable for 95 an ordinary two-stroke cycle in which the air inlet and exhaust are completely controlled by the piston but, of course, the arrangement may be varied and controlling valves also provided if desired. The bottom cylinder cover E is shown as provided with two valves, one a fuel spray valve e^8 and the other an air starting valve e^9 , the latter valve being fitted preferably only to the cylinder cover. While cylinder and piston sleeve ports are shown for an engine of two stroke type the usual valves may be provided for working on a four stroke cycle. 100

105 It will be seen that the cylinder A is free to expand downwardly on expansion by heat, a small clearance being allowed inside the outer wall or water jacket formed by the lower part of the casing, the sliding gas tight joint between the liner or cylinder and the cover E allowing of expansion and contraction. With a construction of engine on the lines described and shown the overall height of the engine is reduced to a minimum and ready access is obtainable, access 110 115 120 125 130

to the interior of the piston being obtained by loosening the fixed abutment and lifting it vertically clear of the engine. On detaching the connecting rods the piston D can be 5 lifted out of the cylinder together with the trunnion ring F so that the interior of the cylinder is readily reached. On the other hand, the lower part of the cylinder can be reached merely by removing the studs e 10 and ring e and lowering the cylinder cover E out of the end of the cylinder (or the cover may be drawn upwards through the cylinder), so that the whole engine can be easily dismantled and any part reached with 15 facility.

What we claim and desire to secure by Letters Patent of the United States is:—

1. In a double-acting internal combustion engine of the type in which fuel is ignited 20 by the heat developed by the compression of a charge of air, a cylinder closed at one end, a fixed abutment of piston type partly closing the other end of the cylinder, a sleeved piston of which the sleeved portion 25 slides over the fixed abutment, which piston forms two combustion spaces, one of which inside the sleeved portion between the piston head and the end of the fixed abutment is smaller than the other between the piston 30 head and the closed end of the cylinder and liquid fuel injection valves for injecting fuel into each of the combustion spaces.

2. In a double-acting internal combustion engine of the type in which the fuel is ignited by the heat developed by the compression of a charge of air, a cylinder closed 35 at its lower end, a fixed abutment of piston type partly closing the upper end of the cylinder, a sleeved piston of which the sleeved portion slides over the fixed abutment, which piston forms two combustion spaces, the lower of which between the piston head and the lower end of the cylinder is larger than the upper combustion 40 space inside the sleeved portion of the piston, a liquid fuel injection valve fitted to the fixed abutment and adapted to inject liquid fuel into the combustion space within the piston sleeve and another liquid fuel 45 injection valve fitted in the opposite end of the cylinder and adapted to inject liquid fuel into the combustion space between the piston head and the cylinder cover.

3. In a double-acting internal combustion 55 engine of the type in which the fuel is ignited by the heat developed by the compression of a charge of air, a cylinder closed at its lower end, a fixed abutment of piston type partly closing the other end of the cylinder, a sleeved piston of which the 60 sleeved portion slides over the fixed abutment, which piston forms two combustion spaces of different capacities, the upper of

which inside the sleeved portion between the piston head and the end of the fixed 65 abutment is of smaller diameter than the other between the piston head and the closed end of the cylinder, inlet and exhaust ports provided in the piston sleeve to serve for the upper combustion space, inlet and 70 exhaust ports in the cylinder corresponding to the said piston sleeve ports and a second set of inlet and exhaust ports in the cylinder adapted to be covered and uncovered by 75 the piston head, and a liquid fuel injection valve fitted to the fixed abutment and adapted to inject liquid fuel into the combustion space within the piston sleeve and another liquid fuel injection valve fitted in the opposite end of the cylinder and 80 adapted to inject liquid fuel into the combustion space between the piston head and the cylinder cover.

4. In an internal combustion engine as claimed in claim 2 a water cooled cylinder 85 liner, a cylinder cover carried by the outer cylinder wall and projecting into the lower end of the cylinder liner, a detachable ring supporting the cylinder cover in position, a cylindrical gas tight joint between the liner 90 and the said cylinder cover which gas tight joint allows of free expansion of the liner relatively to the cylinder cover.

5. In an internal combustion engine a cylinder closed at its lower end, a fixed 95 abutment of the piston type partly closing the upper end of the cylinder, a sleeved piston of which the sleeved portion slides over the fixed abutment, a trunnion member to which the sleeved portion of the piston is secured, which trunnion member is entirely above the upper end of the cylinder, connecting rods externally to the cylinder and connected to the said trunnion member, and liquid cooling means for supplying the piston with cooling liquid 100 through the trunnion member. 105

6. In an internal combustion engine, a cylinder closed at its lower end, a fixed 110 abutment of the piston type partly closing the upper end of the cylinder, a sleeved piston of which the sleeved portion slides over the fixed abutment, a trunnion member to which the sleeved portion of the piston is secured, external connecting rods 115 connected to said trunnion member and liquid cooling supply and outlet pipes for piston connected to the trunnion member and communicating with channels formed in the sleeve portion of the piston, which channels communicate at their lower ends with a cooling chamber formed in the piston. 120

EDWARD HENRY FRIEND.
